WARP STOP MOTION

Harold Marsh, Pawtucket, R. I., assignor to
Draper Corporation, Hopedale, Mass., a
corporation of Maine

Application February 6, 1935, Serial No. 5,269

5 Claims. (Cl. 139—365)

The present invention pertains to warp stop motions for looms and more particularly pertains to the type of such stop motions wherein a toothed detector bar is reciprocated in a toothed holder to detect fallen drop wires.

Warp stop motions of the type mentioned consist of one or more holders which are detachably mounted so as to extend widthwise of the loom, and endwise reciprocating detector bars mounted 10 in the holders. The bars and holders have spaced teeth on their upper edges, to engage a fallen drop wire and thereby effect loom stoppage. The drop wires are supported by the warp threads and are slotted to receive the detector 15 bars and holders. Usually, the teeth on the detector bars project above the teeth on the holders.

In the process of installing a new warp in a loom it is necessary to thread the drop wires 20 onto the detector bar and holder, or to thread the latter into a series of drop wires according to the particular procedure. Also, in the process of repairing a bad "smash" where a large number of warp threads are broken, it is necessary 25 to move a large number of drop wires along the detector bar to make an opening in which to work. In both instances, the projecting teeth on the detector bar and holder so seriously hamper relative movement between the latter and 30 the drop wires as to require the provision of means for facilitating such movement.

Prior to the present invention, it has been the practice to provide sheet metal strips, commonly called "threading bars" to cover the teeth on the 35 detector bars and thus facilitate the aforementioned threading operations. Such strips are not a part of the warp stop motion but are separate therefrom. Consequently, they are awkward and inconvenient to manipulate, and 40 frequently become mislaid or so bent or mutilated as to become valueless.

I propose to eliminate the necessity for such threading bars by so constructing the warp stop motion that the detector bar can be moved to 45 a threading position wherein the teeth on the detector bar project to the same height as the teeth on the holder and fill the spaces between the latter teeth. When in such position, the tops of the teeth on the bar and holder form 50 a continuous surface which offers no opportunity for the drop wires to become caught, and additional parts such as the threading bars are not necessary. In the preferred embodiment of the invention, herein disclosed, the detector bar and 55 holder are constructed to support the bar, alter-

natively, for reciprocation of the bar in an upper position, or in a lower position for the threading operation. The lower position of the detector bar is such that the teeth on the bar and holder occupy the relative positions above mentioned, 5 wherein no threading bars are required.

The said preferred embodiment of the invention is illustrated on the accompanying drawing, of which:

Fig. 1 is a fragmentary perspective view of 10 the warp stop motion comprising said embodiment;

Fig. 2 is a view in elevation, to an enlarged scale, of a portion of the detector bar and holder with the former in operative position; 15

Fig. 3 is a view similar to Fig. 2 but showing the detector bar in threading position; and

Fig. 4 is a view in cross-section taken approximately on line 4—4, Fig. 2.

The warp stop motion shown on the drawing 20 is conventional in many respects, and is mounted on the loom in the conventional manner. Accordingly, there is shown on the drawing only such parts of the stop motion as may be necessary to a clear understanding of the invention. 25

Referring more particularly to Fig. 1, the warp threads W pass from the rear of the loom toward the front thereof and the individual threads each support a drop wire I between warp supporting rods 2 and 3. The drop wires are slotted 30 as at 4 to receive detector bars 5 and holders 6 which extend widthwise of the loom. The drop wires may be arranged in a plurality of rows, thus requiring a plurality of detector bars and 35 holders. These latter parts may be duplicates and, accordingly, but one bar and holder will be described in detail.

Each holder 6 is constructed to support a detector bar and to cooperate with the latter in detecting fallen drop wires. The specific form 40 of holder shown on the drawing is comprised of spaced sides 7, 7 which are connected at their bottoms as by being secured to a metal plate 9. The holder is provided on its upper edge with spaced teeth 10, 10 of conventional form. The 45 holder is detachably fixed in end brackets, of which only the bracket 11 is shown, which brackets are fixed to a loom in the conventional manner.

The detector bar is provided with spaced teeth 50 12, 12 on its upper edge, of slightly greater height than the teeth on the holder. The detector bar is mounted in the holder for endwise reciprocation, i. e. it reciprocates widthwise of the loom. Reciprocation of the bar may be ac- 55

complished by any conventional means such as the yieldable finger 13 which actuates the link 14, the latter detachably engaging a stud 15 in the detector bar.

5 When the detector bar is in operative position in the holder, the teeth 12 on the bar project above the teeth 10 on the holder (Figs. 1 and 2) and the range of movement of the bar is such that each tooth 12 passes back and forth completely past at least one space between the teeth on the holder. It will be apparent that if the only possible position of the detector bar in the holder is the operative position just described, the above-mentioned difficulties in the threading 10 operation will be encountered. The present invention provides for overcoming such difficulties by providing for supporting the bar in a threading 15 position in the holder, as shown in Fig. 3.

It will be noted that in Fig. 3 the detector bar 20 is lowered in the holder so that the teeth 12 on the bar project to the same height as the teeth 10 on the holder and are staggered with respect to the latter teeth so as to coincide with and fill the spaces therebetween. Thus, in the 25 threading position, the top of the assembly comprising the detector bar and holder presents a continuous surface which offers no obstructions to relative movement between the assembly and fallen or unsupported drop wires.

30 In the broader aspects of my invention, the details of the means for alternatively supporting the detector bar in operative or threading positions are not important. The specific supporting means herein disclosed are, however, 35 possessed of certain advantages, they being provided by cutting the bottom edge of the detector bar to form spaced bearing surfaces 16, 16 which cooperate with bearing surfaces 17, 17 formed on the upper edge of the plate 9.

40 The bearing surfaces 16 and 17 are so positioned with regard to the teeth 10 and 12 that they support the detector bar in operative position when the latter is connected with the link 14. To move the detector bar to the threading 45 position of Fig. 3 it is only necessary to disconnect the link 14 and move the bar endwise beyond its normal range of movement whereupon it will drop down to such threading position. It will be noted that the spaces between the bearing 50 surfaces 17 must be slightly longer than the length of the bearing surfaces 16. Preferably, the detector bar is provided with cam surfaces 18 whereby an endwise pull on the detector bar will raise the bar up to operative position as it moves 55 longitudinally from threading position.

Having fully disclosed the preferred embodiment of my invention, I claim:

1. In a warp stop motion for looms, the combination of a stationary holder having spaced 60 teeth on its upper edge, and an endwise reciprocating detector bar mounted in said holder and having spaced teeth on its upper edge; said bar and holder being constructed to support the former for sliding movement in operative position in the holder with the teeth on the bar projecting above the teeth on the holder, and also to support the bar in threading position wherein

the tops of the teeth on the bar are in the same plane as the tops of the teeth on the holder and form with the latter a substantially continuous surface.

2. In a warp stop motion for looms, the combination of a stationary holder having spaced teeth on its upper edge, an endwise movable detector bar having spaced teeth on its upper edge, and means normally supporting said bar for endwise reciprocation within said holder with the teeth on the bar projecting above the teeth on said holder, said means being constructed to also support said bar within said holder with the teeth on the bar projecting to the same height as and staggered with respect to the teeth on the holder for facilitating the threading of drop wires onto the bar and holder. 10 15

3. In a warp stop motion for looms, the combination of a stationary holder having spaced teeth on its upper edge, and an endwise reciprocating 20 detector bar mounted in said holder and having spaced teeth on its upper edge; said bar and holder having cooperating bearing surfaces supporting the bar in operative position wherein the teeth on the bar project above the teeth on the 25 holder, and said holder being constructed to support the bar in threading position wherein the teeth on the bar are aligned laterally of the bar and holder with the spaces between the teeth on the holder and project to the same 30 height as the last said teeth.

4. In a warp stop motion for looms, the combination of a stationary holder having spaced teeth on its upper edge, and an endwise reciprocating detector bar mounted in said holder and having spaced teeth on its upper edge; said bar and holder being constructed to support the bar for reciprocation in an upward position wherein the teeth on the bar project above the teeth on the holder, said bar and holder also being constructed to support the bar in a relatively lower 40 position wherein the teeth on the bar are aligned laterally of the bar and holder with the spaces between the teeth on the holder and project to the same height as the last said teeth. 45

5. In a warp stop motion for looms, the combination of a stationary holder having spaced sides each of which is provided with spaced teeth on its upper edge, and a detector bar reciprocably mounted between the sides of said holder and having spaced teeth on its upper edge; the said bar and holder being provided with cooperating bearing surfaces supporting said bar in operative position with the teeth on the latter projecting above the teeth on the holder, said bearing surfaces and holder being constructed to permit the bar to be lowered in the holder to a position wherein the teeth on the bar are in lateral alignment with the spaces between the teeth on the holder and project to the same height as the last said teeth, the tops of the teeth on the bar and holder forming a substantially continuous surface in a single horizontal plane, to facilitate the threading of drop wires onto the bar and holder. 50 55 60 65
